SHEET HOLDING DEVICE

Gerald D. Austin, Atlanta, Ga., and Michael Wishnovsky, Yeadon, Pa.

Application June 3, 1946, Serial No. 674,007

7 Claims. (Cl. 281—44)

(Granted under the act of March 3, 1883, as amended April 30, 1928; 370 O. G. 757)

1

This invention relates to a holding device, and more particularly to a sheet holding device for holding charts and drawings or other sheet material of considerable length in unrolled condition upon a supporting surface or table.

An object of the invention is to provide a sheet holding device that will hold sheet material of substantial length in unrolled or spread out condition when in use and which is readily raised and which will stay in raised position when desired.

Another object is the provision of a device for holding sheet material or the like, which is movable to variable height depending on the number of sheets placed thereunder.

Still another object is to provide a sheet holding device wherein the holding means will maintain a substantially level plane in relation to the work being held and, therefore an even distribution of pressure is obtained regardless of the elevation of the device due to different thickness of material being held.

A still further object of the invention is to provide a sheet holding device of simple, sturdy, construction which will exert an even holding pressure at all points of the holding means on material on the underlying surface.

Other objects will be apparent from the following description taken in connection with the drawings which are exemplary and in which:

Fig. 1 is a perspective view of a device embodying the invention.

Fig. 2 is a side elevation thereof.

Fig. 3 is a fragmentary sectional view of a detail.

The invention comprises a sheet holding device to be attached to or adjacent a work table or any other desired work holding surface. The invention has particular utility in retaining in readily accessible unrolled condition, sheet material such as drawings or prints for ready removal to an adjacent work unit such as a copying table of micro-photographic equipment or the like.

The attaching member or bracket 1, in the embodiment shown, comprises two parallel vertical uprights of any desired height and spaced at any desired distance apart from each other. The bracket uprights are secured to the table edge by any suitable means, such as screws, wing nuts and bolts, or the like. Positioned near the top of each upright is a hole of any suitable diameter extending laterally therethrough, the holes in the two uprights being in alignment. In these holes is rotatably mounted a shaft 2, the shaft being free to turn or rotate in either direction within the

2

holes in the uprights. The shaft has fixedly mounted thereon as by welding and at substantially 90° thereto an arm member 3. The arm member is so positioned relative to the shaft as to extend beyond the shaft on one side thereof and to extend beyond the shaft on the other side to overlie the material supporting surface A. The longer extension of the arm overlying the surface A is turned down at its outer end forming approximately a right angle, the turned down portion 4 being preferably flattened in such a way that its flattened faces are in alignment with the arm itself, and at 90° to the shaft.

The sheet holding means comprises a bar 5 in parallelism with the arm 3 and preferably positioned with its center point adjacent the flattened, downward extending portion of the arm. The bar 5 is preferably of T-shape, having an upwardly extending flattened stem member 6 at 90° thereto, the upwardly extending member being desirably so formed as to evenly fit face to face with the flattened downward extending portion of the arm. The downwardly extending portion 4 of the arm and the upwardly extending member 6 of the bar are pivotally connected, the pivot 7 being positioned slightly below the mid point of the two members. The upwardly extending member or stem 6 of the bar preferably has thereon a lug or projection 6a on its upper rear edge disposed to limit the pivotal movement of the bar member in one direction by engagement with said arm. Pivotally mounted near each end of the bar 5 are elongated holding members or fingers 15 mounted transversely to the bar. These holding fingers are made desirably of metal, as are all of the members, and can be made of any desired length or diameter. The lower surface of the holding fingers generally form a straight line, but may be formed as required to conform to the contour of the work holding surface. The ends of the fingers are turned up slightly and have mounted thereon balls 10 or any desirable means for rounding the ends for protecting the sheet material from disfiguration. Affixed to the fingers are pivot support members 11 forming an inverted V, the peak of which is formed into a hollow tube 12 to act as a bearing on the bar 5. This pivotal member is retained against lateral movement by having a slot 12a extending around about one-fourth the circumference of the bar receiving tube 12 and a set screw or pin 13 extending through the slot and being threaded into the bar. Thus the fingers or holding members are pivoted on the bar but are affixed to the bar to prevent lateral movement thereon, the pivotal

movement being limited by the length of the slot 12a in the tube.

The holding means thus embodies pivotal means in two directions or planes substantially at right angles to each other, thereby enabling the device to readily conform to the material being held and to apply holding pressure evenly thereto.

A counter-balance means 14 is provided, which may desirably comprise a suitable weight suspended from the rear projection of the arm 3. This weight will act as a counter-balance and when the holding means is lifted to a raised position the holding means is thereby retained in raised position.

In the operation of the sheet holding device, the device being attached to the table or the like in any desirable manner by means of the bracket, it may readily be raised or lowered in respect to the surface of the table. When using the device the operator manually lifts the holding assembly to an up position. The counter-balancing means will then hold the device in this up position. The sheets are then spread out on the table or bench below the holding means, the same then being manually lowered against the sheet material thus holding the sheet material in desired spread out condition. Due to a change in the center of gravity from the up to the down position, the counter-balance means will retain the holding member in an up position, but will not be sufficient to return the fingers from the down to the up position. Therefore the device will remain in a down position until manually raised and the amount of the weight or other counter-balancing means may be adjusted to apply the desired pressure, which will be evenly applied and distributed by the device.

It will be apparent that the device may be adjusted so that the sheet material is held in open condition while being readily removable from beneath the holding members, either by manually raising the holding means or by sliding the sheets laterally from beneath the holding means, for example, for application to an adjacent work unit such as a photo-copying table or the like.

Although but one embodiment of the invention is shown and described, it will be understood that the invention is subject to modification and variation without departing from the spirit of the invention and is only to be limited by the appended claims or the equivalent thereof.

The invention described herein may be manufactured and used by or for the Government of the United States of America for governmental purposes without the payment of any royalties thereon or therefor.

What is claimed is:

1. In a holding device adapted to hold in flat, unrolled position sheets of paper and the like upon a substantially flat holding surface, a bracket having means thereon adapted for mounting said bracket on or adjacent to said material-holding surface, an arm pivotally mounted on said bracket for movement in a substantially vertical plane, said arm extending laterally over said material-holding surface, a bar pivotally mounted on said arm adjacent the end thereof and adapted to oscillate in a plane parallel to the plane of movement of said arm, and an elongated work-engaging finger pivotally mounted transversely on said bar for movement in a plane normal to the plane of movement of said arm.

2. In a holding device adapted to hold in flat, unrolled position sheets of paper and the like upon a substantially flat holding surface, a

bracket having means thereon adapted for mounting said bracket on or adjacent to said material-holding surface, an arm pivotally mounted on said bracket for movement in a substantially vertical plane, said arm having one end extending laterally over said material-holding surface, a bar pivotally mounted intermediate its ends on said arm adjacent said laterally extending end of said arm for free movement in a plane parallel to the plane of movement of said arm, and a plurality of spaced work-engaging members pivotally mounted transversely on said bar for movement in planes normal to the plane of movement of said arm, there being between said work-engaging members unobstructed view of the sheets held by said members.

3. In a holding device adapted to hold in flat, unrolled position sheets of paper and the like upon a substantially flat holding surface, the structure set forth in claim 2 in which said work-engaging members are suspended below said bar and extend laterally on each side thereof.

4. In a holding device adapted to hold in flat, unrolled position sheets of paper and the like upon a substantially flat holding surface, the structure set forth in claim 3 in which means are provided on said bar cooperating with said arm and with said work-engaging members to limit pivotal movement of said bar and said work-engaging members.

5. In a holding device adapted to hold in flat, unrolled position sheets of paper and the like upon a substantially flat holding surface, a bracket having means thereon adapted for mounting said bracket on or adjacent to said material-holding surface, an arm pivotally mounted, intermediate its ends, on said bracket for movement in a substantially vertical plane, said arm having one end extending laterally over said material-holding surface, a bar pivotally mounted intermediate its ends on said arm adjacent said laterally extending end of said arm for movement independently of the motion of said arm in a plane parallel to the plane of movement of said arm, and a plurality of work-engaging members pivotally mounted transversely on and spaced longitudinally of said bar for movement in planes normal to the plane of movement of said arm, there being between said members unobstructed view of the work held by said members.

6. In a holding device adapted to hold in flat, unrolled position sheets of paper and the like upon a substantially flat holding surface, a bracket having means adapted for mounting said bracket on or adjacent to said material-holding surface, an arm pivotally mounted, intermediate its ends, on said bracket for oscillating movement in a substantially vertical plane, said arm having one end extending laterally over said material-holding surface and, during oscillation of said arm, moving toward and away from said surface, a bar pivotally mounted, intermediate its ends, on said arm adjacent said laterally extending end of said arm for oscillating movement, independently of the motion of said arm, in a plane parallel to the plane of movement of said arm, and a plurality of elongated work-engaging members pivotally mounted transversely on and spaced longitudinally of said bar for oscillating movement in planes normal to the plane of movement of said arm, said work-engaging members being suspended below said bar, extending substantially equal distances on each side thereof, and there being between said members unob-

structed view of the work held by said members.

7. In a holding device adapted to hold in flat, unrolled position sheets of paper and the like upon a substantially flat holding surface, a bracket having means adapted for attaching said bracket on or adjacent to said material-holding surface, an arm pivotally mounted, intermediate its ends, on said bracket for oscillating movement in a substantially vertical plane, said arm having one end extending laterally over said material-holding surface and, during oscillation of said arm, moving toward and away from said surface, the outer portion of said arm being bent downwardly to provide a dependent angled extension, the other end of said arm extending outwardly from said material-holding surface in axial alignment with said first-mentioned end and having counterbalancing means supported on its outer end, a bar pivotally mounted, intermediate its ends, on said dependent angled extension of said arm for oscillating movement, independently of the motion of said arm, in a plane parallel to the plane of movement of said arm, said bar carrying adjacent each of its ends, and pivotally mounted thereon, an elongated, transverse, work-engaging member adapted to oscillate in a plane normal to the plane of movement

of said arm, said work-engaging members being suspended below said bar and each extending for substantially equal distances on each side thereof, said bar having projecting means cooperating with said dependent angled extension of said arm for limiting oscillation of said bar in one direction, said arm further having other projecting means cooperating with the mountings of said work-engaging members for limiting oscillation of said members, said counterbalancing means being of such mass as to maintain said work-engaging members raised from said work-holding surface but not to raise said members from work-holding position, and there being between said work-holding members unobstructed view of the work held by said members.
